UNITED STATES PATENT OFFICE.

HERMANN VON DER HEIDE, OF UNNA-KÖNIGSBORN, GERMANY.

WATERPROOFING AND WEATHERPROOFING COMPOSITION.

1,177,156.

Specification of Letters Patent. Patented Mar. 28, 1916.

No Drawing.

Application filed June 18, 1914. Serial No. 845,848.

To all whom it may concern:

Be it known that I, HERMANN VON DER HEIDE, a subject of the German Emperor, residing at Unna-Königsborn, in Germany, 5 have invented a certain new and useful Improved Waterproofing and Weatherproofing Composition, of which the following is a specification.

This invention relates to an improved 10 agent for water and weather proofing, particularly, porous stone and plastering materials, earthy and fibrous insulating materials and the like.

For the purpose of water proofing porous 15 plaster, stone or the like surfaces, it has already been proposed to coat the same with a solution of soap.

These attempts, however, have yielded no 20 satisfactory results, as ordinary solutions of soap, even after having dried in, are easily re-dissolved by water with the exception of a few particles, which have been converted into water repelling fatty acid salts through 25 chemical interaction with salts, such as for instance soluble salts of calcium, magnesium, aluminum and the like, which are accidentally to be found in the coated surface. Further, it has already been attempted to increase the effect of the solution of soap by 30 following up the first coat of soap solution with a second coat of solutions of salts of aluminum, calcium, magnesium or similar metals. Apart from the greater trouble involved by the application of two such coats, 35 this method has been successful only partially, inasmuch as the insoluble fatty acid salt was formed generally on the surface only, whereas owing to the water repelling effect of the first coat of soap solution, 40 which, although insufficient for practical purposes, is nevertheless very pronounced at first, the second coat was unable to penetrate into the deeper pores.

The object of this invention is to provide 45 a water and weather proofing agent, by means of which these disadvantages are completely removed and one coat of which will insure absolutely waterproof properties of the most porous kind of mortar or stone, 50 even under the most adverse meteorological

conditions, which may occur in actual practice.

It has been found that by mixing alkaline or ammoniacal solutions of different metallic hydroxids such as zinc, copper, lead, tin, 55 chromium or aluminum, in which the acid properties of the metallic hydroxid are more active than the basic properties, with a solution of soap (fat soap or resin soap, the alkali metal of which may be replaced 60 wholly or partly by ammonia), a deposit of the metal salts of fatty acid which are insoluble in water and which after drying possess water-repelling properties to a high degree, is not formed; on the contrary the 65 ingredients after being mixed together form more or less clear solutions which may be mixed with water. These solutions are drawn like water into the pores of any porous stone, mortar or similar materials 70 and the formation of the respective water-repelling fatty acid metallic salt takes place only during drying. The respective metallic salts, after a short period of drying of the materials, wetted with the same, are thus 75 not only uniformly distributed over the surface thereof, but also everywhere deep down in the pores, thus rendering the respective material completely water-repellent, *i. e.* water proof even under the most adverse 80 conditions.

Having thus described my invention what I claim as new and desire to secure by Letters Patent is:—

1. A waterproofing and weatherproofing 85 composition comprising a solution in an excess of alkali of a soap which is insoluble in pure water.

2. A waterproofing and weatherproofing 90 composition comprising a solution in an excess of ammonia of a soap which is insoluble in pure water.

In testimony whereof I have signed my name to this specification in the presence of two subscribing witnesses.

HERMANN VON DER HEIDE. [L. S.]
